US00D980590S

(12) United States Design Patent (10) Patent No.: US D980,590 S
(45) Date of Patent: * Mar. 14, 2023

(54) SHOE

(71) Applicant: VALENTINO S.p.A., Milan (IT)

(72) Inventor: Pierpaolo Piccioli, Milan (IT)

(73) Assignee: VALENTINO S.p.A., Milan (IT)

() Term: 15 Years

(21) Appl. No.: 29/765,497

(22) Filed: Jan. 8, 2021

(30) Foreign Application Priority Data

Jul. 10, 2020 (IT) 402020000002164

(51) LOC (14) Cl. 02-04

(52) U.S. Cl.

USPC D2/926; D2/916
